(57) CLAIM

The ornamental design for an air pump, as shown and described.

DESCRIPTION

FIG. 1 is a frontal perspective view of the air pump showing my new design;

FIG. 2 is a frontal perspective view of the air pump of FIG. 1, an attachment portion which is not part of my new design being shown in broken lines;

FIG. 3 is a right side view of the air pump of FIG. 1;

FIG. 4 is a front view of the air pump of FIG. 1;

FIG. 5 is a top plan view of the air pump of FIG. 1;

FIG. 6 is a left side view of the air pump of FIG. 1;

FIG. 7 is a rear view of the air pump of FIG. 1; and,

FIG. 8 is a bottom plan view of the air pump of FIG. 1.
